INVENTOR,

Alfred W. Terry,
BY
W. H. Griswold.

ATTORNEY.

UNITED STATES PATENT OFFICE.

ALFRED W. TERRY, OF BROOKLYN, NEW YORK.

ANTI-FRICTION BEARING.

SPECIFICATION forming part of Letters Patent No. 396,968, dated January 29, 1889.

Application filed November 3, 1888. Serial No. 289,859. (No model.)

To all whom it may concern:

Be it known that I, ALFRED W. TERRY, of Brooklyn, in the county of Kings and State of New York, have invented a certain new and useful Improvement in Anti-Friction Bearings, of which I declare the following to be a full, clear, and exact description, reference being had to the accompanying drawings, forming part of this specification.

10 This invention relates to improvements in anti-friction bearings in which the bearing-surface is composed of a system of rollers; and the invention consists of an anti-friction roller-bearing constructed as herein described 15 and claimed.

In the accompanying sheet of drawings, Figure 1 is a cross-section of the bearing applied to a sheave. Fig. 2 is a part sectional view of the same in the planes $x x$, Fig. 1. 20 Figs. 3 and 4 are respectively end and side views of the system of rollers.

Similar letters of reference indicate like parts in the several views.

This invention is particularly applicable to 25 sheaves, and was made with special regard to its use in that connection; but it may also be applied to the various other objects for which bearings of this class are suitable.

While the drawings show the bearing as 30 part of a sheave, its construction and application in all cases will be readily understood from these drawings and the description.

On each of three or more pins, $a a a$, is 35 loosely mounted a pair of short rolls, $b b$, and on each of a corresponding number of pins, $a' a' a'$, is loosely mounted a single roll, b' , of the same diameter as the rolls $b b$. The ends of these pins are secured at equal 40 distances apart to two flat rings, $A A'$, placed with their axes in common, the pins $a a a$ alternating with the pins $a' a' a'$ in a series, all being parallel to and equally distant from the axis of the rings, and each of the rolls $b' b' b'$ on the pins $a' a' a'$ passing between 45 the rolls $b b$ of each of the two pairs of rolls adjacent thereto on the pins $a a a$, as illustrated in Figs. 1 and 4.

The system of rollers, arranged and united as described, is inclosed by a shell, B , open 50 at the ends, and having rims c to retain the rollers in position. The rims c are both shown as integral parts of the shell B , and when they are formed in this manner the

rollers must be placed in the shell before the rings $A A'$ are permanently united to all the 55 pins; but one of the rims can be made removable, if desired, and then the rolls may be permanently secured together before they are placed in the shell.

All the rollers come in contact with the 60 shaft C , which passes through the center of the system, as shown in Figs. 1 and 2, and they all roll upon the inner surface of the shell B , the office of the pins $a a'$, &c., being merely to cause the rolls to maintain their 65 proper relative positions.

The shell B is attached in any suitable manner to the sheave, or to whatever object it may be desired to apply the bearing.

On each of the pins a' , instead of a single 70 roll b' , may be mounted two such rolls, the additional rolls being placed between one of the outer rows of rollers, as they appear in Fig. 4, and the adjacent ring A or A' , the length of the pins and of the bearing being 75 increased accordingly; and still other rollers may be added in a similar manner, either on the pins $a a a$ or on the pins $a' a' a'$, the arrangement of the rolls in all cases being such as has been explained. 80

Having now described my invention, what I claim as new, and desire to secure by Letters Patent, is—

1. An anti-friction bearing consisting of the rings $A A'$, united by the series of pins $a a'$, 85 arranged alternately, as set forth, the pins $a a'$, $a' a'$ of said series having mounted thereon rolls $b' b' b'$, and the remaining pins $a a a$ having mounted thereon rolls $b b$, each roll b' passing between two of the rolls $b b$ on either 90 side of the same, substantially as and for the purpose described.

2. In an anti-friction bearing, the combination of the rings $A A'$, the series of pins $a a'$, arranged alternately, as set forth, the rolls $b b$, 95 arranged in pairs, one pair on each of the pins $a a a$, and the rolls $b' b' b'$, one on each of the pins $a' a' a'$, each roll b' passing between the rolls $b b$ of each of the two pairs on each side of the same, substantially as and 100 for the purpose described.

ALFRED W. TERRY.

In presence of—

G. M. PLYMPTON,
D. A. CARPENTER.
